UNITED STATES PATENT OFFICE

2,450,109

WALK-IN REFRIGERATOR COOLED BY A
FORCED AIR CIRCUITClinton C. Brinkoeter, San Antonio, Tex., assignor
to Ed Friedrich, Inc., San Antonio, Tex., a cor-
poration of Texas

Application August 28, 1946, Serial No. 693,523

7 Claims. (Cl. 62—102)

1

My invention relates to refrigerators of the walk-in type, i. e. such as are used by florists, butchers, etc.

The invention has for its objects:

1. To provide a walk-in type of cooler which can be located in a corner of a room adjacent to the ceiling.
2. To provide a cooling unit which, for a room of a given cubic foot capacity, will be more efficient than those heretofore known.
3. To provide a cooling unit of a simple construction which will effectively serve its intended purposes.

Other objects will in part be obvious and in part will be pointed out hereinafter.

To the attainment of the aforesaid objects and ends invention further resides in the novel details of construction, combinations and arrangements of parts, all of which will first be described in detail hereinafter and then be specifically pointed out in the appended claims, reference being had to the accompanying drawings in which

Fig. 1 is a vertical longitudinal section of a walk-in cooler embodying my invention, the section being taken on the line 1—1 of Fig. 2.

Fig. 2 is a horizontal section on the line 2—2 of Fig. 1.

Fig. 3 is an enlarged detail horizontal section on the line 3—3 of Fig. 4.

Fig. 4 is an elevation of the parts shown in Fig. 3 looking in the direction of the arrow *a* in Fig. 3.

Fig. 5 is a vertical section on the line 5—5 of Fig. 2.

Fig. 6 is a detail elevation of the coil back plate having the large simple perforations in its upper part and smaller air-scoops in its lower part.

Fig. 7 is a detail elevation of the blower showing the intake side.

Fig. 8 is a detail sectional perspective view on the line 8—8 of Fig. 2.

In the drawings in which like numerals and letters of reference indicate like parts in all the figures, 1 represents the bottom or floor of the chamber to be cooled, 2 the side and end walls, 3 a doorway or opening, and 4 a perforated ceiling.

The outer shell 6 is insulated with suitable heat-cold insulation 5 as is also the door 7, a base trim 8 is provided as usual. A top plate 9 is spaced above the foraminous ceiling 4 and holds the insulation 5 above it against falling to the ceiling 4. By this construction a space is left which comprises a top duct 10.

The refrigerating unit, by means of which the

2

temperature within the room R is lowered to a definite degree, is now located in a corner of the room adjacent the ceiling 4 and includes a removable main front plate 11 having fastening or mounting flanges 12 secured in any suitable way, as by screws, for example, to the adjacent walls 2, and a removable upper front plate 15 having side flanges 16 for securing to the side walls 2. The plate 11 has an opening 14 into which the edges of the plate are bent as at 13. The plate 11 is also secured to the bottom plate 17 of the unit. The plate 17 has a drain hole 18 and a front flange 19 to which flange a baffle 20 is also secured.

The refrigerator unit also includes two side walls 21 which lie against the adjacent walls 2 of the room.

The space between the bottom 17 and the plate 9 above is divided into a warm air receiving chamber 23 and a cooling chamber by a transverse partition 22 having an air discharge opening 24 and serving to support a centrifugal fan or blower 25 whose outlet registers with the opening 24. The partition 22 also supports the drive motor 26 for the blower 25. The plate 15 serves as a removable front for the chamber 23.

Below the partition 22 is a 45° baffle plate 27 which extends from one side plate 21 to the other and terminates at the upper end of a vertical partition 28 that is spaced from the foraminous plate 31 to leave a vertical down duct 30, the plate 28 having a bottom extension 29 spaced above the bottom plate 17 and cooperating with an extension 34 of plate 31 below the cooling coil unit, the plate 31, above the level of the lower end of the baffle 27, has relatively large simple scoop holes 32 and below that level has smaller scoop-like openings 33.

The space between the opening 14 and plate 31 is filled with the cooling coil 35 and its fins 36.

The coils 35 at the bottom join a header 37 and at the top they join a header 38. A liquid refrigerant line 39, which includes a suitable expansion valve 41, connects to the header 37 while a suction duct 42 connects with the header 38, the duct 42 and a part of the line 39 are enclosed in a casing 40 forming a heat interchanger.

Provision is made for lubricating the motor 26 without removing the front plate 15 by the provision of an oil line 45 having a suitable inlet fixture 46. The power outlet for the motor is indicated by 47.

The drain hole 18 connects with an off-take duct 44 having a suitable trap 43 to hold water

55 as an air seal.

Assuming that a suitable refrigerant is flowing through the coil 35 and that the blower 25 is operating, air will be drawn into duct 10, via the holes in ceiling 4, and from thence into chamber 23 to blower 25. The blower then forces the air down against baffle 27 by which it is deflected forwardly downwardly through the holes 32 and scoops 33 between the fins 36 and over the coils 35 to and through the opening 14 into the chamber to be cooled.

From the foregoing description, taken in connection with the accompanying drawings, it is thought that the construction, operation and advantages of my invention will be clear to those skilled in the art.

What I claim is:

1. In a walk-in cooler having a room bounded by a top wall, side and end walls and a floor, and having a perforated ceiling spaced from said top wall to provide an air duct, the improvement which comprises: an air-cooling and circulating unit located in one corner of the room adjacent said ceiling and above said floor, said unit including a blower and motor chamber in communication with said air duct and a cooling chamber below said blower and motor chamber, a motor-driven blower in said blower and motor chamber, the blower receiving air from said blower and motor chamber and forcing it down into said cooling chamber, and means in said cooling chamber for cooling the air passing through said cooling chamber and passing the air into said room.

2. In a walk-in cooler having a room bounded by a top wall, side and end walls and a floor, and having a perforated ceiling spaced from said top wall to provide an air duct, the improvement which comprises: an air-cooling and circulating unit located in one corner of the room adjacent said ceiling and above said floor, said unit including a blower and motor chamber in communication with said air duct and a cooling chamber below said blower and motor chamber, a motor-driven blower in said blower and motor chamber, the blower receiving air from said blower and motor chamber and forcing it down into said cooling chamber, and means in said cooling chamber for cooling the air passing through said cooling chamber and passing the air into said room, said cooling means includes a cooling coil, upper and lower headers for said coil, an expansion line which includes an expansion valve and is connected to said lower header, a duct connected to said upper header, and a casing enclosing a portion of said expansion line and said duct as a heat interchanger.

3. In a walk-in cooler having a room bounded by a top wall, side and end walls and a floor, and having a perforated ceiling spaced from said top wall to provide an air duct, the improvement

which comprises: an air-cooling and circulating unit located in one corner of the room adjacent said ceiling and above said floor, said unit including a blower and motor chamber in communication with said air duct and a cooling chamber below said blower and motor chamber, a motor-driven blower in said blower and motor chamber, the blower receiving air from said blower and motor chamber and forcing it down into said cooling chamber, and means in said cooling chamber for cooling the air passing through said cooling chamber and passing the air into said room, said means for cooling includes a cooling coil, a back plate adjacent said coil and having openings in its upper portion and air scoops in its lower portion, and down-air-duct from the blower to and along said back plate.

4. In a walk-in cooler having an air duct between a top wall and a foraminous ceiling, the improvement which comprises: an air circulating and cooling unit located in a corner of the cooler adjacent said ceiling, said unit including a vertical front wall secured across said corner and having an opening, a cooling coil adjacent said opening and in back of said vertical front wall, a horizontal partition located above said cooling coil and having an opening, a motor-driven blower for receiving air from said air duct and forcing it below said horizontal partition, a foraminous vertical partition in back of said coils, a deflecting partition against which air from the blower is driven and by which it is deflected to the cooling coil, and a duct from the lower end of said deflecting partition to the lowermost coil, said foraminous vertical partition having air passages for purposes described.

5. A walk-in cooler according to claim 4 wherein there is a partition below and spaced from said coil and having a drain-hole and a front flange, and a deflecting plate projected through the opening in said vertical front wall and secured to said flange.

6. A walk-in cooler according to claim 4 wherein there is a partition below and spaced from the coil and having a drain-hole, a trapped drain duct leading from said hole to the outside of the cooler.

7. A walk-in cooler according to claim 4 wherein means are provided by which the motor may be oiled from the outside of the cooling unit.

CLINTON C. BRINKOETER.
